UNITED STATES PATENT OFFICE.

RICHARD E. SMITHER, OF PHILADELPHIA, PENNSYLVANIA.

GAME APPARATUS.

1,286,439.

Specification of Letters Patent.

Patented Dec. 3, 1918.

Application filed April 19, 1918. Serial No. 229,590.

To all whom it may concern:

Be it known that I, RICHARD E. SMITHER, citizen of the United States, residing at Philadelphia, in the county of Philadelphia and State of Pennsylvania, have invented 5 certain new and useful Improvements in Game Apparatus, of which the following is a specification.

This invention is a game apparatus and 10 has for its principal object the production of an out-door game which is not only entertaining, as well as beneficial to physical conditions, but which may also be played by any number of participants and upon fields 15 which, due to irregular surfaces or like conditions, would prevent the playing of a great many ordinary games.

Another object of this invention is the 20 production of a game apparatus wherein a stand is provided upon which the whirl is placed, thus permitting the bat to be gripped and permit the participant to strike the whirl and drive the same in the direction of a goal.

25 Another object of this invention is the production of a game apparatus wherein a stand is so arranged as to permit either right handed or left handed batters to participate with equal ease.

30 A still further object of this invention is the production of a game apparatus wherein the stand is arranged to permit the same to be shifted to allow the batter to more easily direct the whirl toward a desired goal.

35 Another object of this invention is the production of a game apparatus wherein the pivoted arms for releasably holding the whirl are held against rotation in one direction by reinforcing braces, although these 40 arms are free to swing in the opposite direction in the event they are accidentally struck, thus preventing injury to these arms.

45 Another object of this invention is the production of a game apparatus comprising an elongated body which is reduced intermediate its ends to permit a resilient ball to be carried thereon, although the ends of the body are somewhat frusto-conical in shape, thus permitting the whirls to be easily carried 50 upon the arms of the stand.

Broadly stated, this invention includes the provision of a stand which comprises a base

section having a post mounted thereon, diagonally extending base boards fixed upon said post, outwardly extending parallel bars 55 carried by said base boards, arms pivotally mounted upon the ends of said bars, braces holding said arms against rotation in one direction, and a whirl having a resilient portion intermediate its end resting upon said 60 arms, thus permitting a bat to be gripped and strike the resilient body of the whirl to drive the same toward a desired goal.

With these and other objects in view, this 65 invention consists of certain novel combinations, constructions and arrangement of parts as will be hereinafter fully described and claimed.

One practical form of the present invention will be hereinafter described and is illustrated in the accompanying drawings, in 70 which—

Figure 1 is a front elevation of the stand, portions of the stand being broken away and shown in section. 75

Figure 2 is a side elevation of the stand, portions of the base and the post being broken away. 75

Figure 3 is a side elevation of the whirl, a 80 resilient body being shown in section.

Figure 4 is a fragmentary side elevation of the bat.

Figure 5 is a diagrammatic plan view of the 85 playing field, illustrating the position of the stand and the goals, and

Figure 6 is a detail plan view of a portion of the stand illustrating the manner in which an arm is held from rotation in one direction.

In the preferred embodiment of this invention, about to be described, 10 indicates the base of the stand, as shown in Figs. 1 and 2. This base 10 is provided with a sharpened lower end 11, thus permitting the driving of the base into the ground, until the upper end of the base extends adjacent the surface, as illustrated in Fig. 1. 90

This base is provided with a socket 12 extending into its upper end as shown in Fig. 1 and illustrated in dotted lines in Fig. 2. 100

The post 13 has a pin 14 projecting from its lower end and this pin 14 extends into the socket 12 of the base 10, thus causing the post to be positively supported upon the

stand, although, it is obvious the post may be turned when desired. This post is considerably longer than the base and for this reason extends for a considerable distance 5 above the surface of the ground in order to make the portions of the stand upon which the whirl is supported to be in convenient position for access by a participant in the game.

10 A base board is positioned upon each side of the post 13 and it will be noted, upon referring to Fig. 1, that these base boards 15 are in parallel alinement. Accordingly, bolts 16 are passed through the boards and 15 also through the posts 13 to receive the nuts 17, thus firmly holding the boards upon the post 13. Particular attention is invited to the fact that these base boards extend diagonally across the post 13 in planes extending 20 substantially 60° for purposes to be hereinafter set forth. The bars 18 are firmly held in engagement with the base boards 15 in any suitable manner. These bars are carried in pairs upon each base board and 25 are spaced from each other in parallel planes as shown in Figs. 1 and 2. It will be seen that these bars 18 extend for considerable distance beyond the outer surface of these base boards, thus permitting free access to 30 the ends of the bars without interference from the post or the base boards.

The supporting arms 20 comprise comparatively flat elongated strips which bear upon the outer ends of the supporting bars 35 18. Retaining elements 21 are formed on the arms 20 and are carried upon the outer ends of the pins 19 extending from the outer ends of the bars 18, thus holding the arms against accidental displacement, although 40 the arms are permitted to rotate for purposes to be set forth. The clips 22 are fixed upon the outer ends of the arms 20 and these clips are curved in cross section to 45 present supporting trough like structures upon which the whirls are releasably supported.

To hold the arms against rotation in one direction, diagonal strips 23 are fixedly secured as indicated at 24 upon the inner surfaces 50 of the supporting bars 18 adjacent the outer ends of these bars. The brace strips 23 extend diagonally from the bars and project in the path of movement of the arms and thus it will be seen that the arms will 55 rest upon the projecting ends of these brace strips 23, as illustrated clearly in Figs. 1, 2 and 6. Accordingly, the arms may be held against rotation in one direction by these strips, although if the arms are accidentally 60 struck by the participant batting, the arms will swing to prevent injury thereto. It will also be noted that the arms carried by the upper supporting bars 18 extend downwardly, while the arms carried by the 65 lower supporting bars 18 extend upwardly.

Owing to the diagonal arrangement of the base boards it is obvious the arms will extend in planes extending diagonally across the post, as will be seen by referring particularly to Fig. 2.

70

The whirl used in connection with this invention consists of an elongated structure, such for instance as a stick which is reduced at 25 intermediate its ends. The ball 26 which is formed of rubber or other similar 75 material is positioned upon the reduced portion 25 of the whirl. The end portions are substantially frusto-conical as shown at 27, and these ends are slightly larger than the reduced portion 25, thus holding the ball 26 80 against longitudinal displacement. The extreme end portions 28 of the whirl are substantially cylindrical and are reduced, thus causing the whirl to be easily carried upon the clips 22, as illustrated in Fig. 1. As the 85 clips are curved in cross section but have a broad open front portion, it is obvious the whirl may be easily struck and knocked from engagement with these clips without injuring the stand. Furthermore, since the 90 extreme ends are cylindrical, it is obvious the whirl will be supported very easily by the clips and owing to the extension of the boards and the diagonal extension of the arm, the whirl will be held in the position 95 indicated in Fig. 1.

The bat 29 may be of any suitable construction and is illustrated clearly in Fig. 4. This bat 29 is provided at its outer end with a metallic sleeve 30 for increasing the 100 weight of the bat, at this end.

In connection with the playing field, attention is directed to Fig. 5 wherein the field is illustrated in diagram, A stand is placed as indicated in this figure and then 105 goals 31 may be formed at different intervals from this stand and the goals will have a different value, as indicated in Fig. 5. These goals may be formed in the ground by digging a pit of any suitable size, or may be 110 several boards secured together, at their ends, to form a pen, or any other suitable structure.

In playing the game, as many persons as desire may enter the same as it is intended 115 to have each participant provided with a number of whirls of uniform colors, that is the whirls of each participant will be different from the color of the whirls of the other participant or participants. In accordance with the direction of the goal, the participant is playing for, the stand is turned by rotating the post upon the base 120 of the stand. Then the participant may place his whirl upon either side of the stand, 125 in accordance with the desires of the participant, whether he is a left or right handed batter. The participant then grips the bat and secondly swings the same forwardly and slightly upwardly into engagement with 130

the resilient ball 26, thus causing the bat to drive the whirl toward a desired goal. As the bat is weighted and since the whirl is comparatively light, it is obvious the 5 whirl will be easily driven, thus preventing undue exertion or straining of the body of the participant. The participant is preferably provided with a number of whirls, and then after he has driven the whirls toward 10 the desired goals, the remaining participant or participants may in turn drive their whirls likewise until all the whirls have been driven. After this the participant then adds up the points he has scored, according 15 to the whirls remaining in the pits or pens constituting the various goals, and the participant having the highest number of points wins the game. If desired whirls which land in the pits or pens and then bounce 20 out may also be counted.

As the arms are held against rotation in one direction, it is obvious they will hold the whirls in set positions, although if either of the arms is accidentally struck, it will 25 swing forwardly and thus prevent injury to the arm.

From the foregoing it will be seen that an out-of-doors game apparatus has been constructed which is so formed as to permit 30 a person to play individually or allow any number of participants to play, thus producing a pleasing and entertaining game. It will also be noted that necessary swinging of the bat, which is somewhat similar to the 35 swinging of a base-ball bat, an ax, golf stick, or the like, will physically benefit the participant. Also, since the goals are placed at spaced distances from the stand, the condition of the intervening ground does not 40 interfere with the playing of the game and in fact the game can be played on a comparatively small field if desired.

The foregoing description and the drawings have reference to what may be considered the preferred, or approved, form of my 45 invention. It is to be understood that I may make such changes in construction and arrangement and combination of parts, materials, dimensions, et cetera, as may prove 50 expedient and fall within the scope of the appended claims.

Having thus fully described my invention, what I claim as new and desire to secure by Letters Patent, is:—

55 1. A game apparatus comprising a movably supported post, a base board carried by said post, supporting bars carried by said base board in spaced relation, and supporting means on the ends of said supporting 60 bars, thus permitting a whirl to be carried upon said supporting means and to be driven therefrom.

65 2. A game apparatus comprising a post, a base board carried upon said post, supporting bars carried by said base board, movable

arms carried upon said bars, means for holding said arms against movement in one direction, and a whirl positioned upon said arms, thus permitting the whirl to be driven therefrom, and the pivotal supporting of 70 said arms preventing the arms from being injured if accidentally struck.

3. A game apparatus comprising a frame consisting of a post, means for supporting said post, a diagonally extending base board 75 carried upon said post, supporting bars carried by said division board adjacent the ends thereof, arms carried upon the ends of said bars, said arms extending toward each other, thus causing the arms to be in a plane 80 extending diagonally across the longitudinal axis of said post, and a whirl removably resting upon said arms, thus permitting the whirl to be struck and driven from the arms when desired. 85

4. A game apparatus comprising a stand, said stand including a pair of parallel supporting bars, arms pivotally mounted upon the ends of said bars, said arms extending in a diagonal plane with respect to the 90 longitudinal axis of said stand, means for holding said arms against rotation in one direction, and a whirl carried upon said arms, thus permitting the whirl to be struck from said arms and the support of said arms 95 permitting the same to move if accidentally struck, thus preventing injury to said arms.

5. A game apparatus comprising a stand, said stand including parallel supporting bars, arms pivotally mounted upon the outer 100 ends of said bars, curved clips carried by the ends of said arms, brace strips carried by said bars and engaging said arms for holding said arms against rotation in one direction, and a whirl resting upon said clips, 105 thus permitting the whirl to be struck between the clips and the support of said arms also permitting the same to move, if accidentally struck thus preventing injury to said arms. 110

6. A game apparatus comprising a stand consisting of a base, a post turnably mounted upon said base, diagonally extending base boards upon opposite sides of said post, bars carried by said base boards, supporting 115 arms carried by the ends of said bars, means for holding said arms against rotation in one direction, and a whirl removably resting upon a plurality of said arms.

7. A game apparatus comprising a stand, supporting arms carried by said stand, and a whirl engaging said supporting arms, said whirl consisting of a reduced central portion having a resilient ball thereon, enlarged frusto-conical portions extending from the 120 reduced central portions and cylindrical end portions extending from the frusto-conical portions, thus causing the cylindrical end portions to be carried by said arms, thus permitting the whirl to be struck upon the re- 125 130

silent ball and driven from engagement with said arms.

8. A game apparatus comprising a frame including a diagonally extending base board, supporting bars carried by said base board adjacent the ends thereof, arms carried upon the ends of said bars, said arms extending toward each other, thus causing the arms to be in a plane diagonally crossing the vertical axis of said frame and a whirl removably resting upon said arms.

9. A game apparatus comprising a stand, said stand including a pair of parallel supporting bars, arms pivotally mounted upon the ends of said bars, said arms extending in a diagonal plane with respect to the vertical axis of said stand, brace strips carried by said bars for holding said arms against

rotation in one direction, and a whirl carried upon said arms.

10. A game apparatus comprising a stand consisting of a base, a post turnably mounted upon said base, base boards carried upon opposite sides of said post, bars carried by said base boards, supporting arms carried by the ends of said bars, means for holding said arms against rotation in one direction, and a whirl removably resting upon a plurality of said arms.

In testimony whereof I affix my signature 30 in presence of two witnesses.

RICHARD E. SMITHER.
